(57) **CLAIM**

The ornamental design for a drinking glass, as shown and described.

DESCRIPTION

FIG. 1 is a perspective view of the drinking glass according to the invention; and,

FIG. 2 is a side perspective view of the drinking glass.
A drinking glass is wholly made out of transparent material and has an upwardly open mouth and a flat base on which it stands. The sides are double-curved and the structure is rotation symmetrical about a normally upright axis.
